UNITED STATES PATENT OFFICE.

CHARLES L. HEISLER, OF SCHENECTADY, NEW YORK.

LOCOMOTIVE AND LOCOMOTIVE-TENDER.

1,186,779.

Specification of Letters Patent. Patented June 13, 1916.

Application filed September 8, 1915. Serial No. 48,633.

To all whom it may concern:

Be it known that I, CHARLES L. HEISLER, a citizen of the United States, and resident of Schenectady, county of Schenectady, and State of New York, have invented certain new and useful Improvements in Locomotives and Locomotive-Tenders, of which the following is a specification, and which are illustrated in the accompanying drawings, forming a part thereof.

The object of the invention is to provide improved means, located in part on the locomotive and in part on the tender, for moving the coal forward in the fuel bin of the tender; and one embodiment of the invention is fully hereinafter described and is illustrated in the accompanying drawings, in which—

Figure 1 is a detail central vertical section of a locomotive and tender; Fig. 2 is a detail plan view thereof, some parts being removed; and Fig. 3 is a detail, in section, of the connection between a motor located on the locomotive and the coal pushing mechanism located on the tender.

A part of the frame of a locomotive is represented at 10; the back wall of its fire-box at 11; its fire-door opening at 12, and the floor of its cab at 13.

A part of the frame of the tender is represented at 14, and at 15, 16 and 17 are shown, respectively, the side wall, the rear inclined wall, and the bottom of the fuel bin. The fuel bin is provided with a supplemental floor extending forwardly from the lower portion of its inclined wall 16, the rearward sections 18 of this floor being preferably curved from rear to front, and its forward section 19 constituting the horizontal shoveling floor or plate, and is preferably substantially on a line with the bottom of the firing door opening 12 of the locomotive.

Fuel pushing elements are provided for advancing the fuel to the shoveling platform, and comprise a plurality of pusher heads 20, 21, shown as two in number, the one movable on the inclined wall 16 and the other over the curved floor section 18. The heads are connected together by means of rigid links 22, 23, preferably attached thereto at their ends. The front face, as 24, of each pusher head is abrupt, and its upper face, as 25, is inclined downwardly, the pusher, therefore, being substantially wedge-shaped in cross-section, its forward face forming an abutment for advancing the fuel,

while its rearward portion is so shaped as to slide easily under the fuel as the pusher head is moved backwardly.

A motor 26, shown as of the reciprocating type, is mounted on suitable brackets secured to the locomotive frame 10, and its piston 27 is connected by means of a rod 28 with the forward pusher head 21, this connection being by means of a suitable bracket 6 secured to the head and extending through a longitudinal slot 29 in the floor section 18. The rod 28 is formed of two sections united by any suitable connection, such as the union joint 30, thereby permitting the tender to be separated from the locomotive.

In order to provide for lateral movement of the rod 28 incident to the movement of the pusher head 21 over the curved floor section 18, and also incident to the relative lateral movement of the locomotive and tender, the rod is connected with the piston 27 by means of a ball and socket joint 31, and the piston is provided with a sleeve 32 which passes through and reciprocates in the cylinder head 33, the sleeve being of greater diameter than the rod.

The motor 26 being located at a lower level than the floor of the tender, is inclined upwardly at its rear end, and when the construction of the tender is such as to render it necessary a channel, as represented at 34, is formed in the forward portion of the tender tank 35 to accommodate the rod 28.

While the rear section 18 of the floor over which the forward pusher head travels is preferably curved, as shown, this form is not essential, it being important, however, that an incline leading up to the shoveling platform be provided over which the coal is pushed.

A plate 36, attached to the pusher head 21, covers the slot 29 to prevent fuel from dropping therethrough, and this plate extending both forwardly and backwardly from the pusher head the slot is always closed thereby.

A steam pipe 37 leads to the motor 26, and is provided with a valve 38 located at any convenient point where it will be easy of access.

Various changes in the details of construction may be made without departing from the scope of the invention.

I claim as my invention—

1. In combination a locomotive a tender having a fuel bin, means for advancing

- fuel forwardly over the floor of the tender, and a motor located upon the locomotive, and an operating connection between motor and coal-advancing means.
5. In combination, a locomotive, a tender therefor having a fuel bin and a shoveling plate, a pusher for advancing fuel to the shoveling plate, a motor located on the locomotive, and operating connection between the motor and pusher.
10. In combination, a locomotive, a tender therefor having a fuel bin and a shoveling plate, a pusher for advancing fuel to the shoveling plate, and a motor located on the locomotive and having a vibrating piston rod, such rod being connected with the pusher.
15. In combination, a locomotive, a tender therefor having a fuel bin and a shoveling plate, a pusher for advancing fuel to the shoveling plate, and a reciprocating motor located on the locomotive and having its piston and piston rod connected by a universal joint, such rod being connected with the pusher.
20. In combination, a locomotive, a tender therefor having a fuel bin and a shoveling plate, a pusher for advancing fuel to the shoveling plate, and a reciprocating motor located on the locomotive and having its piston and piston rod connected by a universal joint, such rod being connected with the pusher.
25. In combination, a locomotive, a tender therefor having a fuel bin, a pusher for advancing fuel to the shoveling platform of the bin, and a reciprocating motor having its piston provided with a tubular stem slideable through a head of the motor and a piston rod connected with the piston by a universal joint and extending through the stem, such rod being connected with the pusher.
30. In combination, a locomotive, a tender therefor having a fuel bin and a shoveling plate, a pusher for advancing fuel to the shoveling plate, a motor located on the locomotive, and operative connection between the motor and pusher head, the rod connecting the motor and pusher being sectional, the sections being detachably united.
35. In combination, a locomotive and tender
- therefor, the tender having a fuel bin and an elevated shoveling platform at the forward end of the bin, a pusher reciprocable over the floor of the tender, a motor located on the locomotive, and a rod connecting the motor and pusher and being located below the shoveling platform.
40. In combination, a locomotive, a tender having a fuel bin, the bottom thereof being concave, and an elevated shoveling platform at the forward end of such bottom, a pusher reciprocable over the concave bottom, a motor located on the locomotive, and a rod connecting the motor piston with the pusher.
45. In combination, a locomotive, a tender having a fuel bin, the bottom thereof being concave, and an elevated shoveling platform at the forward end of such bottom, a pusher reciprocable over the concave bottom, a motor located on the locomotive, and a rod connecting the motor piston with the pusher and being located below the shoveling platform.
50. In combination, a locomotive, a tender having an inclined back wall, a concave bottom and an elevated shoveling platform at the forward end of such bottom, a pair of pusher heads reciprocable, respectively, over the inclined wall and bottom of the bin and being linked together, a motor on the locomotive, and a rod connecting the motor piston with the pusher heads.
55. In combination, a locomotive having a floor and a fire-box provided with a firing door, a tender having a fuel bin and provided with a shoveling plate elevated above the locomotive floor, a pusher for advancing fuel in the bin to the shoveling plate, a motor located on the locomotive, and operative connection between the motor and the pusher.
60. In combination, a locomotive, a tender having an inclined back wall, a concave bottom and an elevated shoveling platform at the forward end of such bottom, a pair of pusher heads reciprocable, respectively, over the inclined wall and bottom of the bin and being linked together, a motor on the locomotive, and a rod connecting the motor piston with the pusher heads.
65. In combination, a locomotive, a tender having an inclined back wall, a concave bottom and an elevated shoveling platform at the forward end of such bottom, a pair of pusher heads reciprocable, respectively, over the inclined wall and bottom of the bin and being linked together, a motor on the locomotive, and a rod connecting the motor piston with the pusher heads.
70. In combination, a locomotive, a tender having an inclined back wall, a concave bottom and an elevated shoveling platform at the forward end of such bottom, a pair of pusher heads reciprocable, respectively, over the inclined wall and bottom of the bin and being linked together, a motor on the locomotive, and a rod connecting the motor piston with the pusher heads.
75. In combination, a locomotive, a tender having an inclined back wall, a concave bottom and an elevated shoveling platform at the forward end of such bottom, a pair of pusher heads reciprocable, respectively, over the inclined wall and bottom of the bin and being linked together, a motor on the locomotive, and a rod connecting the motor piston with the pusher heads.
80. In combination, a locomotive, a tender having an inclined back wall, a concave bottom and an elevated shoveling platform at the forward end of such bottom, a pair of pusher heads reciprocable, respectively, over the inclined wall and bottom of the bin and being linked together, a motor on the locomotive, and a rod connecting the motor piston with the pusher heads.
85. In combination, a locomotive, a tender having an inclined back wall, a concave bottom and an elevated shoveling platform at the forward end of such bottom, a pair of pusher heads reciprocable, respectively, over the inclined wall and bottom of the bin and being linked together, a motor on the locomotive, and a rod connecting the motor piston with the pusher heads.
90. In combination, a locomotive, a tender having an inclined back wall, a concave bottom and an elevated shoveling platform at the forward end of such bottom, a pair of pusher heads reciprocable, respectively, over the inclined wall and bottom of the bin and being linked together, a motor on the locomotive, and a rod connecting the motor piston with the pusher heads.
95. In combination, a locomotive, a tender having an inclined back wall, a concave bottom and an elevated shoveling platform at the forward end of such bottom, a pair of pusher heads reciprocable, respectively, over the inclined wall and bottom of the bin and being linked together, a motor on the locomotive, and a rod connecting the motor piston with the pusher heads.
